UNITED STATES PATENT OFFICE.

ARTHUR W. LE BOEUF, OF WOONSOCKET, RHODE ISLAND, ASSIGNOR TO ELECTRIC COMPOSITOR COMPANY, OF NEW YORK, N. Y., A CORPORATION OF NEW JERSEY.

ESCAPEMENT MECHANISM FOR LINE-CASTING MACHINES.

Specification of Letters Patent. Patented Aug. 25, 1914.

1,108,378.

Application filed December 13, 1912. Serial No. 736,490.

To all whom it may concern:

Be it known that I, ARTHUR W. LE BOEUF, a citizen of the United States, residing at 208 Carrington avenue, city of Woonsocket, in the county of Providence, and State of Rhode Island, have invented a certain new and useful Improvement in Escapement Mechanism for Line-Casting Machines, of which the following is a full, clear, and exact description.

This invention is an improvement upon the escapement mechanism which is disclosed in and covered by Letters Patent No. 791,131.

The object of the invention is to provide a construction such that when it is operated to release a matrix or spacer, one, and only one, matrix or spacer will be released from the associated magazine; and also to prevent the matrices from pounding through the magazines where the matrices during the distribution thereof are dropped into their respective magazines. The present invention involves the use of a star wheel substantially like that which is shown in said prior patent; and the invention consists in the novel mechanism by which to control the movements of that star wheel. Experience has shown that with the star wheel controlling mechanism which is shown in said prior patent, sometimes two or more matrices will be released from the magazine as the result of one actuation of the star wheel controlling mechanism. When the star wheel is released, it will turn until an arm thereof strikes the stop finger on the pallet lever, thereby releasing one matrix. When the star wheel arm strikes the stop finger, that ought to bring the star wheel to a stand still. But as a matter of fact, since the blow of the star wheel arm against the stop finger on the pallet lever is delivered in a direction tending to rock said pallet lever, it sometimes does cause this pallet lever and associated reed and key lever to teeter or vibrate back and forth with such amplitude as to release the star wheel one or more additional times, and thereby to release one or more additional matrices. Occasionally also the star wheel will rebound or turn backward when one of its arms comes against the stop finger of the pallet lever, and this backward movement is sometimes great enough to allow a second matrix to escape. Sometimes also, the matrices or

spacers will "pound through" as they are distributed, *i. e.* dropped into their magazines. This is more likely to take place when the magazines are nearly empty, and this action, when it takes place is due to the following action of the parts. A matrix when dropped into the top of a magazine will acquire considerable momentum as it falls and before it is stopped either by engaging directly with the star wheel arm, or with the upper matrix of the matrices which are supported by that star wheel arm. When the matrix is so stopped it may rebound,—and may also cause the matrices below it to bound up,—and the star wheel to turn backward. If the matrices bound high enough and the star wheel turns backward far enough, when the matrices again descend there may be no arm of the star wheel projecting into their path and as a result one or more of them may drop through. This action, which is called "pounding through," does not often take place, but does take place occasionally with the old construction, especially when the magazine contains no matrices or only one when a matrix is dropped into it.

The invention shown in the drawing and herein described and claimed will prevent the vibration of the escapement mechanism referred to, and will also prevent the "pounding through" of the matrices; and one form thereof will also prevent the release of matrices through the rebounding of the star wheel when the escapement is operable.

The invention is adapted for use in association with finger keys to release matrices from their magazines; and also is adapted for use in association with certain mechanism for controlling the release of justifying spaces from a spacer magazine.

In the drawing Figure 1 is a sectional side elevation of the mechanism as it may be constructed for use in conjunction with manually operable key levers for releasing matrices. Fig. 2 is a sectional plan on line 2—2 on Fig. 1. Fig. 3 is a sectional side elevation of a modification of this invention, adapted to be operated by properly timed mechanism, to release justifying spacers.

Referring to the parts by reference characters, having particular regard to Fig. 1, 5 represents a matrix magazine, the same being a vertical channel adapted to contain a

vertical column of matrices M resting one upon another.

3 represents the associated star wheel which is pivoted to a fixture, and has four arms which are adapted to successively project into the associated channel through a slot in the rear wall thereof. The several arms are indicated by 3^a, 3^b, 3^c, 3^d.

1 represents a detent lever which is pivoted to a suitable fixture. Its forward end extends to a position such that it will normally engage the downwardly extended star wheel arm 3^b when the forwardly projecting star wheel arm 3^a is projecting in substantially horizontal direction into the magazine, so as to extend beneath the lowest matrix, and support the entire matrix column. The rear end of this detent lever projects into a notch 6^a in the front edge of a vertically movable reed 6; and the lower end of this reed rests upon the rear end of a key lever 7. By depressing the front end of the key lever, the reed is raised, and the detent lever 1 is moved so as to release its engagement with the star arm 3^b, whereupon the weight of the column of matrices acting on arm 3^a will cause said star wheel to turn. This permits the falling of the lowest matrix out of the bottom of the matrix magazine; but when the star wheel does so turn the next arm 3^d of the star wheel—the one which had been projecting upward—will insert itself beneath the next to the lowest matrix. In order to stop the star wheel at a suitable point so that this arm may support the matrix column, the stop lever 2 is provided. This is pivoted to a suitable fixture, and extends down from its pivot, and it has in its lower edge a notch 2^a which receives an upwardly extended finger 1^a, which is a part of the detent lever 1. Any movement of either lever 1 or 2 is necessarily accompanied by a reciprocal movement of the other lever; that is to say when one lever moves into the path of the star wheel arms, the other moves out, and vice versa. As will be seen from the drawing, when the front end of the detent lever 1 is engaging the star wheel arm 3^b, the lower end of lever 2 is out of the path of the star wheel arms; but when the lever 1 is rocked so as to release the downwardly extended star wheel arm, the stop lever 2 will at the same time be moved into the path of that arm, so that its lower end will be struck by said arm, thereby temporarily stopping said star wheel. The blow which the star wheel arm applies to the lever 2 when it strikes it, is in an upward direction, that is to say, toward the pivot, and therefore does not tend to rock said stop lever 2, nor consequently, the detent lever 1. This blow therefore does not tend to impart to lever 1 and the mechanism connected with it any such teetering or vibrating motion as is sometimes imparted to the correspond-

ing parts of the mechanism shown in said prior patent.

When the key lever 7 is released the weight of the associated reed is such as will cause these two levers to rock to their normal positions. This carries the front end of the detent lever 1 into the path of the star wheel arm 3^a, and it likewise withdraws the operative end of the stop lever 2 from its engagement with the star wheel arm 3^b, and this permits the star wheel to turn through a short arc into substantially the position shown in the drawing.

Additionally there is a rebound pawl 4 provided. This, in the construction shown in Fig. 1, is an independently pivoted pawl located above the star wheel, and normally projecting into the path of the star wheel arms. When the star wheel turns in the matrix releasing direction, as shown by the arrow, the upwardly extended arm will engage this pawl and lift it and pass it before the rearwardly projecting arm engages with the stop lever. The pawl will thereafter fall behind the upper arm of the star wheel; wherefore if, when the rearwardly pointed arm of the star wheel engages the stop lever 2, there is any tendency of the star wheel to rebound, that is to turn in the reverse direction, this turning movement will be prevented by the rebound pawl 4. This pawl normally occupies this position, and therefore obstructs any such backward turning of the star wheel as would result in releasing a matrix, and which might result from the pounding action of a matrix dropped into the magazine.

The construction shown in Fig. 3 is as stated especially adapted for use in releasing justifying spaces from magazines 11, which are similar to the matrix magazines. This construction is substantially like that shown in Fig. 1, except that the pawl 4^a is made integral with the stop lever 2. This is desirable because it lessens the cost of the mechanism, and because it eliminates the possibility that the pawl may fail to act to prevent pounding through. In the construction shown in Fig. 1, it is possible that the pawl 4 may get stuck in its elevated position—or, if not that, it may by chance be up when the pounding through tendency is manifested. But with the construction shown in Fig. 3 this cannot happen. The mechanism for operating the escapement levers 1 and 2 is substantially such as is shown and described in the pending application of B. F. Bellows, Serial No. 507,918. That is to say, each lever 1 is under the influence of a spring 13 tending to move it in the releasing direction. It is restrained from so moving by a cam 16 which is turned slowly by suitable mechanism first in the direction to release lever 1 and allow its spring to move it, and then in the reverse direction to move it back again.

direction to restore lever 2 to its original position. The timing of the movements of the cam insures the proper action of the parts with which it cooperates. The pawl 4^a does not prevent the rebounding of the star wheel when the escapement is operated, but this is not so necessary in a construction where the escapement is operated by properly timed mechanism, as it is in the construction shown in Fig. 1, which is to be operated by operators whose touch upon the keys will vary greatly.

The relative cheapness of the construction shown in Fig. 3 and the certainty that the pawl 4^a will always act to prevent pounding through makes this the preferred construction for timed mechanically operated escapement mechanism. It would also be preferred for manually operated escapement mechanisms, except for the fact that the touch of the operators vary. One who would release the key levers too slowly might thereby so delay the return of pawl 4^a to its normal position that a matrix could pound through before said pawl did assume the position wherein it would prevent this operation.

Those familiar with this art will understand that the described escapement mechanism is provided for and associated with each magazine. The part 20 which is shown in Fig. 1 is no part of the present invention. It is, in fact, a movable locking bar which when in the position shown, prevents the operation of all of the escapement mechanisms. When the machine is in condition for assembling matrices through the actuation of the escapement, this locking bar is to be moved out of the way.

Having described my invention, I claim:

1. In escapement mechanism, the combination with a magazine adapted to contain small pieces of metal such as matrices and spacers, and a rotatable star wheel disposed so that its arms may project into said magazine, with a detent lever adapted for movement such as will carry it into or withdraw it from the path of the star wheel arms, a stop lever adapted for movement into and out of the path of said star wheel arms, said two levers being respectively provided with a notch, and a finger which projects into said notch whereby they are compelled to move reciprocally.

2. In escapement mechanism, the combination, with a magazine adapted to contain small pieces of metal such as matrices and spacers, and a rotatable star wheel disposed so that its arms may project into said magazine, with a restraining detent lever adapted to engage one arm of the star wheel to prevent the rotation of the latter in one direction or to move out of the path of said arm to permit said rotation, a stop lever adapted to be moved into and out of the path of a star wheel arm reciprocally with respect to said detent lever, said stop lever carrying a pawl which is placed so as to project into the path of said star wheel arms, while said stop lever does not project into said path, and vice versa.

In testimony whereof, I hereunto affix my signature in the presence of two witnesses.

ARTHUR W. LE BOEUF.
